ACCOUNTING MACHINE

Walter A. Anderson, Bridgeport, Conn., assignor
to Underwood Elliott Fisher Company, New
York, N. Y., a corporation of Delaware

Application December 31, 1937, Serial No. 182,683

11 Claims. (Cl. 101—93)

This invention relates generally to business and accounting machines, and more particularly to machines of the character on which it becomes necessary or desirable, from time to time, to change the type in the type carriers thereof. The present application is a continuation in part of my co-pending United States application Serial No. 118,597, filed December 31, 1936.

As is well known to those skilled in the art, machines of the type disclosed herein are provided with type carriers adapted to be raised and stopped differentially during the first portion of a cycle of the machine and returned during the latter portion of said cycle.

The primary object of this invention is to provide a device to facilitate the changing of interchangeable type in one or more of these type carriers.

With this and incidental objects in view, the invention consists in certain novel features of construction and combinations of parts, the essential elements of which are set forth in appended claims, and a preferred embodiment of which is hereinafter described with reference to the drawings which accompany and form part of the specification.

In the drawings:

Figure 1 is a perspective view of the machine with the arresting device operated and one of the type carriers in its uppermost position, wherein the type may be readily replaced,

Figure 2 is a diagrammatic view of the keyboard.

Figure 3 is a right side elevation of the arresting device and certain associated parts in their normal positions just after the motor bar is depressed but before the machine has started, certain of the parts being broken away for clearness.

Figure 4 is a view similar to Figure 3 with the parts shown in substantially mid-cycle position.

Figure 5 is a view similar to Figure 3 but with the parts shown in the position they occupy at the completion of the cycle during which the arresting device has been operated.

Figure 6 is a perspective view of certain parts of the device including the automatic type carrier release in unoperated position.

Figure 7 is a right side elevation of the parts shown in Figure 6, showing them in operated position.

Figure 8 is a detail right side elevation of the type character latch, showing it holding a type character in the carrier.

Figure 9 is a view similar to Figure 8 with

the type character latch moved to its unlatching position preparatory to the changing of the type character.

Figure 10 is a detail elevation of certain parts used to automatically restore character keys, and

Figure 11 is a side elevation, showing the connection between the main drive and the type bars.

General description

The present invention is shown embodied in a computing and printing machine of a type similar to that disclosed in Patent No. 2,088,982, issued to Oscar J. Sundstrand on August 3, 1937, to which reference may be had for an understanding of features not fully disclosed herein.

Machines of this character are provided with type carriers arranged side by side and adapted to be moved independently and differentially upwardly into printing position during the first part of a machine cycle and then downwardly into normal position during the latter part of the cycle.

When it is desired to change a type in one of these type carriers, it is necessary that the associated carrier be raised and held in its uppermost position so that the type to be changed is accessible to the operator. In the present structure a special key is provided which, when moved to operative position and the machine operated, withdraws the customary zero stops for the type bars to allow them to rise to their uppermost positions, and arrests the operation of the machine when they arrive at this position. To return the machine to normal after the necessary type change is made, it is only necessary for the operator to return the special key to its normal position.

Detailed description

Referring to Figure 1, the machine includes the usual type carriers 1, a platen 2, a carriage 3 supporting the platen, a keyboard 4 having a section of character keys indicated at 5 and amount keys 6. A motor bar 7 controls the starting of an electric motor 8 and the engagement of the drive clutch (not shown) to cause the cycling of the machine.

Suffice it to say at this time, that depression of the motor bar 7 causes the motor circuit to be closed and the drive clutch to be engaged, whereupon the crank 9 (Figure 3) is rotated counter-clockwise through its connection to the drive shaft 10. A pitman 11 is pivotally connected at one end to the crank 9 and at its opposite end to an actuating arm 12. This actu-

ating arm 12 is loosely mounted intermediate its ends on a shaft 13 journaled in a bracket 14 secured to the machine frame. A lever 15 is secured at its lower end to shaft 13 and carries at its upper end a laterally projecting pin 16, for a purpose to be later described. A strong spring 18 is connected to lever 15 at 17, and to the machine frame. Intermediate the ends of this lever 15 is a projection 19, the rounded end of which is adapted to overlie and abut the upper edge of the free end of actuating arm 12, at 20, by virtue of the rearward tension exerted by spring 18 upon the lever 15.

From the above it is apparent that as crank 9 is rotated by drive shaft 10, pitman 11 oscillates actuating arm 12 which in turn oscillates lever 15. A stud 21 is provided in projection 19 of lever 15, to which is pivoted a connecting link 22, the forward end of which is pivoted, at 23, to a plate 24 secured to an auxiliary shaft 25 rotatably journaled in an upwardly and forwardly extending bracket 26 secured to bearing 14.

To secure a smooth and uniform operation of these and other parts in the machine, as it is cycled, there is provided a counter-balance 27^a (Figures 6 and 7) secured to shaft 25 beside plate 24. Obviously as lever 15 is swung forward and back during the cycle, connecting link 22 oscillates plate 24, shaft 25, and counter-balance 27^a. The motor circuit (diagrammatically illustrated in Figure 5) includes a pair of normally open contact members 27 and 28 having a common center strap 29, which are adapted to be closed by either of two laterally projecting and insulated studs 30 and 31 lying on opposite sides of the contacts 27 and 28.

These insulated studs are secured respectively to a pair of co-acting slides 32 and 33 mounted side by side on shouldered screws or rivets 35 which pass through elongated slots 36 in the slides and are secured to the side plate 37 of the machine frame.

A spring 38 secured at one end to an upstanding lug 39 on the rear end of slide 33 and anchored at its opposite end to the machine frame, tensions said slide and the insulated stud 31 forwardly, so that an upstanding lug 40 on the upper edge of the slide normally presses against a laterally extending pin 41 carried by slide 32.

Another spring 42, superior to spring 38, is secured at one end to a depending lug 43 on the forward end of slide 32 and at its opposite end to the machine frame, thus tensioning the slide and the insulated stud 30 rearwardly. A detainer 45 is pivoted at 46 to slide 32 and has a shoulder 47 adapted to engage a square stud 48 on the machine frame. A spring 49 secured at its lower end to a pin 49^a carried by the detainer, and at its upper end to a pin 49^b carried by the stem of the motor bar 7, tensions the detainer upwardly about its pivot 46 and holds it against pin 49^b.

When the machine is at rest, contacts 27, 28 and 29 are open, as illustrated in Figure 5.

The motor bar 7 is normally urged upwardly by a coil spring 50 (Figure 3) fastened at one end to the vertical stem of the motor bar and at its opposite end to the machine frame.

As the motor bar 7 is depressed from the position shown in Figure 5 to the position shown in Figure 3, pin 49^b lowers the detainer 45, moving shoulder 47 away from stud 48 and thereby releasing slide 32 and the insulated stud 30 for rearward movement by spring 42 against the tension of the inferior spring 38. This movement of stud 30 moves contact 27 against con-

tact 29, and the latter in turn against contact 28 to close the motor circuit, stud 31 at the same time moving rearwardly away from contact 28. As soon as the operator releases the motor bar 7 it is restored under the influence of spring 50, 5 the spring 49 pulling the detainer 45 upwardly so that the upper edge just in front of the shoulder 47 is pressed against the lower side of stud 48.

Closure of these contacts, together with engagement of the clutch (not shown), causes operation of drive shaft 10, lever 15 and counter-balance 27^a as above described.

As lever 15 moves counter-clockwise about its axis 13 to the position shown in Figure 4, pin 16 engages an arm 51 extending upwardly from the 15 rear end of slide 32, and moves it forward against the tension of spring 42.

This forward movement of slide 32 brings shoulder 47 out from under stud 48 and thus permits detainer 45 to swing upwardly about its pivot 20 40. Simultaneously, pin 41 moves forwardly away from lug 40 and thus permits spring 38 to move slide 33 forward. This moves the parts from the position shown in Figure 3 to that shown in Figure 4.

This movement of slide 32 moves insulated stud 30 forward, opening contacts 27, 28 and 29. However, the momentum of the motor continues to move slide 32 forward, allowing spring 38 to continue to move slide 33 forward, thereby causing insulated stud 31 to move contact 28 forward. This closes contacts 27, 28 and 29 and allows the machine to continue its operation. The motor then operates until arm 15 moves stud 16 rearwardly away from arm 51. Spring 42 thereupon moves slides 32 and 33 rearwardly to the position shown in Figure 5, where shoulder 47 rests against stud 48 and the contacts are open. Spring 42 then pulls lever 15, actuating arm 12 and shaft 13 to their home positions shown in Figure 3.

Referring to Figure 11, an arm 131 is secured to shaft 13 and has secured to it stud 21 (shown also in Figure 4). A link 132 connects arm 131 with a lever 133 having an arm 134 pivoted to a link 135, guided by a rod 136 and connected by springs 137 to a lever 138 pivoted on a rod 139. A duplicate train of connections, including an arm 131, a link 132, a lever 133 and a link 135, are provided at the opposite side of the machine so that a rod 140, extending between the lower ends of the two links 135, may pull down simultaneously upon the springs 137 connected with levers 138, there being a lever 138 for each type bar 1. A pair of cams 141, only one of which is shown, 55 lying on opposite sides of the machine, are connected by a rod 142, lying above the forward ends of levers 138, and embrace a rod 143 that extends between the lower ends of levers 133, and which supports the rear ends of links 132. Each of the cams 141 has a cam slot 144 embracing identical rollers 145 mounted on stationary parts of the machine.

When the machine is operated, moving stud 21 forward, as previously explained, levers 133 are 65 rotated clockwise about their pivot 146, lowering links 135 and stretching springs 137. This movement is accompanied by a raising of cams 141 and rod 142. Levers 138 lift their associated type bars 1 until they are arrested under control of 70 stop mechanism such as disclosed in U. S. Patent No. 1,965,611, issued to Oscar J. Sundstrand. The return movement of arm 131 lowers cams 141 and rod 142, returning levers 138 and the remaining parts to their original position. This actuation 75

of the type bars is quite similar to that disclosed in Patent No. 1,965,611.

With reference now particularly to Figures 6 and 7, a manually controlled slide 52 is slidably mounted on the machine frame and carries at its forward end an upstanding finger-piece 54. A plate 55 is pivoted on the machine frame at 56 and is connected to slide 52 at 57. An angularly formed stop lever 58 also is pivoted at 56 and is provided at its upper forward end with a pin 59 to which is secured a spring 60, anchored at its opposite end on plate 55, thus urging pin 59 against the rear edge of plate 55, and yieldingly holding lever 58 against clockwise movement about stud 56.

The end 61 of lever 58 lies in the plane of a pin 62 secured to the inner side of the counter-balance 27a.

When slide 52 is in its rearward position shown in Figure 6, the rear end 61 of lever 58 is below the path of movement of pin 62, but when slide 52 is moved forwardly to the position shown in Figure 7, the end 61 of lever 58 is swung upwardly into the path of pin 62.

A spring tensioned detent 63 serves to maintain the slide in either of the two aforesaid positions.

With reference now to Figure 4, when the counter-balance 27a is swung counter-clockwise with the slide 52 in its forward position shown in Figure 7, pin 62 engages the upper edge of the end 61 of lever 58 and rocks the lever downwardly to the dotted line position shown in Figure 7, stretching the spring 60. When pin 62 slides past the end 61 as shown in Figure 4, spring 60 pulls lever 58 upwardly into the path of the pin. Hence, shortly after the beginning of the clockwise oscillation of counter-balance 27a on the return stroke of the cycle, pin 62 engages the end 61 of stop lever 58 and thereby locks counter-balance 27a, plate 24, link 22 and lever 15 in their forward or half-way positions of the cycle, as shown in Figure 5.

The slight clockwise movement of the above parts from the position shown in Figure 4 to the position shown in Figure 5 before pin 62 abuts stop lever 58 permits the rearward movement of slides 33 and 32 necessary to open the motor circuit contacts 27, 28 and 29 as above described, and allows crank arm 9 and pitman 11 to move beyond the dead center position shown in Figure 4. The machine is now at rest in substantially mid-cycle position, with spring 18 tensioned.

Any type carrier whose detent has been removed from above the upstanding rod connected to the associated type bar is permitted to rise during the first portion of the cycle, as above mentioned. Hence, when slide 52 is operated and the machine stopped at mid-cycle position, such carrier is stopped in raised position. The following parts are provided to automatically remove the appropriate detent as an incident to operation of slide 52.

Referring to Figures 6 and 7, type carriers (only one being shown in these views) have forwardly projecting pivoted arms, such as 64, connected to vertically disposed stop rods, such as 65, arranged to be guided for vertical movement through suitable openings (not shown) in the machine frame.

A key latch slide, such as 66, is provided for each of the banks of character keys. These slides 66 are tensioned rearwardly by springs 67 and are arranged for movement forwardly and rearwardly of the machine, and have a rearwardly extending detent 68 arranged to overlie the rods 65, as shown

in Figure 6. A plurality of upstanding lugs 69 are formed on the upper edge of these slides. Each lug has a beveled surface 70 and a locking shoulder 71, so arranged that the beveled surface is directly beneath a locking lug, such as 72, provided on each of the key stems 73. Each key stem 73 is connected with a bell crank 74 pivoted on an axis 75 and connected at its opposite end to a horizontally disposed stop 76, the rearward end of which is supported in a slot provided in the rear of the key section casing.

Compression springs 77 are arranged to normally urge stops 76 forwardly and thus through the bell crank connection with the key stem 73, hold the key in raised position. Depression of any key in the group causes its corresponding stop 76 to move rearwardly against the tension of its spring 77 into the path of its corresponding rod 65. Simultaneously, lug 72 cams slide 66 forward against the tension of spring 67 until it engages shoulder 71. Such forward movement of slide 66 withdraws detent 68 from above rod 65 to allow the corresponding carrier to rise, in the ensuing cycle, until its rod 65 abuts the projected stop 76.

Means is provided for restoring any of the depressed keys 5 near the completion of a cycle. Such means includes a plate 78 secured to a transversely slidable rod 79 journaled at its ends in the machine frame.

The lower edge of plate 78 lies behind an upstanding projection, such as 80, formed on the forward ends of each slide 66. A spring 81 secured at one end to a collar fixed to rod 79 and at its opposite end to a bracket 82 tensions plate 78 and rod 79 counter-clockwise and normally holds a projection 83 of the plate against bracket 82. A slot 84 is provided in plate 78 to receive the forward hook-shaped end 85 of a slide 86. Slide 86 is provided (Figure 10) with an extension bent 40 at a right angle to its main body. A screw 87 passes through a slot in the extension to act as a guide for the forward and rearward movement of the slide. A pitman 88, lying parallel to and adjacent slide 86, is pivotally connected at its rear end to an upwardly extending arm 89 of a plate 90 pivoted at 91. Plate 90 is arranged to be oscillated, first clockwise, then counter-clockwise about its pivot, once during each cycle of the machine. This movement is imparted to plate 90 by an arm 92 fixed to the main rock shaft 13 and having a roller 93 on its outer end engaging a recess 94 in plate 90. During each machine cycle arm 92 is rocked counter-clockwise approximately 75 degrees from the normal position shown in Figure 10 and then clockwise to normal position. On the counter-clockwise stroke roller 93 is moved out of recess 94, and by its movement along the lower edge of plate 90, cams the plate clockwise against the tension of springs 96 and 97, and moves pitman 88 rearward. It should be noted that spring 97 is positioned so as to create an upward as well as a forward tension on pitman 88. On the clockwise stroke of arm 92 plate 90 is swung counterclockwise by springs 96 and 97, moving pitman 88 forward.

During the first part of the machine operation, when pitman 88 moves rearwardly, a stud 100, lying normally under an extension 101 on the rear end of slide 86, moves to the rear of this extension 70 and, due to the tension of spring 97, is lifted into the horizontal plane of the extension. The upward movement of pitman 88 is limited by a stud 102 on the machine frame. During the latter part of the cycle, when pitman 88 is moved for-

ward, stud 100 contacts the rear end of extension 101 and through this contact moves slide 86 forward, moving plate 78 forward against the tension of spring 81. This withdraws shoulders 71 of slides 66 from stop lugs 72 of any depressed keys, allowing them to be restored by their springs 71. As pitman 88 approaches the end of its forward movement, a beveled surface 98 thereon contacts a roller stud 99 on the machine frame, forcing the forward end of the pitman downward, lowering stud 100 from the horizontal plane of extension 101, and thereby allowing spring 81 to return plate 78 and slide 86 to their normal positions shown in Figure 10.

15 It is sometimes desirable to have a key 5 of a group remain depressed during repeated cycling of the machine. To accomplish this, the following means is provided. Plate 78 is arranged to be moved laterally to one of three positions with respect to projections 80 of slides 66. Such movement of plate 78 is controlled by a lever 103 pivoted on a stud 104 on bracket 82 and having a slot engaging a pin 105 in rod 79. A notched detent 106 engaging the lower end of lever 103 serves to maintain plate 78 in any of its adjusted positions. Notches 107 are so arranged in plate 78 that when the plate is moved to certain of its lateral positions the notches are selectively opposite projections 80, in which instance they are ineffective to operate slides 66. Thus any key 5 of a group which is depressed when plate 78 is moved so that one of its notches 107 is opposite projection 80 of the latch slide 66 of that group, will not be released at the end of a machine operation.

40 The following means is provided for automatically rocking plate 78 clockwise to withdraw detents 68 from over rods 65 of the type carriers coincident with operation of the mid-cycle arresting device. The outer end of an arm 108 (Figure 6) secured to rod 79 is arranged to engage a projection 109 on the forward end of slide 52, regardless of the lateral adjustment of rod 79. Hence, when slide 52 is moved forwardly from the position shown in Figure 6 to that shown in Figure 7, projection 109 rocks plate 78 forwardly and thus pulls slides 66 forward, removing detents 68 from over rods 65. The spring of detent 63 is superior to the combined strength of springs 67 of the latch slides and spring 81; hence, plate 78 and slides 66 are maintained in such position until slide 52 is moved rearward. It might be noted that before slide 52 is operated, lever 103 should be in its normal position shown in Figure 6, wherein plate 78 is so positioned that projections 80 of all slides 66 will be engaged by the plate.

45 Assuming it is desired to change the "year" type character "36" controlled by key 110 (Figures 1 and 2), it is merely necessary for the operator to pull the finger piece 54 of slide 52 forward to the position shown in Figures 1 and 7 and depress motor bar 1. This causes the machine to operate to and stop at the mid point of the cycle, as hereinbefore described, the type carrier containing the character "36" rising to and stopping at its uppermost position shown in Figure 1, wherein the type may be readily changed, in the manner described in the following.

50 Referring now to Figures 8 and 9, the carrier 1 is provided at its upper end with a latch 111 situated between the side plates of the carrier and mounted for sliding movement to the right and left (Figure 8) as well as a slight pivotal movement about a pin 113 secured to the side plates

of carrier 1 and extending through a slot 112 in slide 111 (compare Figures 8 and 9).

55 A downwardly projecting lug 114 is provided on the forward end of the latch 111 and is formed angularly as at 115 at its lower and forward edge for cooperative engagement with a recess 116 provided in the forward end of type 117, as shown in Figure 8. A spring 118 is secured to an upstanding lug 119 on the rear end of latch 111 and to a stud 120 extending between the side plates of the 10 carrier 1, to tension latch 111 and type 117 forwardly.

15 In normal printing operations, type 117 is moved to the right (Figure 8) by the customary printing hammer, the type carrying latch 111 15 with it against the tension of spring 118. As the hammer retracts, spring 118 returns the latch and type to normal position. During this reciprocation, latch 111 is guided horizontally at its left end by type 117 and at its right end by stud 20 113.

25 An upstanding finger piece 123 is provided on the latch adjacent a recess 124. In order to change the type character 117 the operator need only press the finger piece 123 against the tension 25 of spring 118 to move the latch 111 rearwardly until recess 124 is in alignment with stud 123, thence upwardly until the recess engages the stud, as shown in Figure 9.

30 During such rearward movement, the downwardly projecting lug 114 is moved out of its engagement with recess 116 in type 117 and thereby allows removal of the type and insertion of another of similar shape, bearing "37" on its face.

35 It is apparent that spring 118 serves the two-fold purpose of holding the latch in locking position with relation to the type, as shown in Figure 8, and returning the type 117 after an impression is effected by the printing hammer.

40 After the type is changed, finger piece 54 is pushed rearwardly, forcing stop lever 58 downwardly out of the path of pin 62, releasing counter-balance 27, plate 24, connecting link 22 and lever 15 to the tension of spring 18 that restores them from the position shown in Figure 5 to the normal position shown in Figure 3. The machine is now in condition to be used for its customary work.

45 While the form of mechanism herein shown and described is admirably adapted to fulfill the objects primarily stated, it is to be understood that it is not intended to confine the invention to the exact embodiment herein disclosed, for it is susceptible of embodiment in various forms all coming within the scope of the claims which follow.

50 What is claimed is:

1. In a machine of the class described, a movable type carrier, a type removably mounted thereon, actuating elements moving with said carrier, manipulative means for arresting the movement of said actuating elements whereby to stop said carrier at a position to facilitate the changing of type thereon, and means controlled by the manipulative means for returning the carrier to normal position.

55 2. In a machine of the class described, operating mechanism, a type carrier adapted to be independently advanced and retracted during a machine operation, a type removably mounted on the carrier, and key controlled means for arresting operation of the machine when the carrier reaches substantially its fully advanced position.

3. In a machine of the class described, operat-

ing mechanism, a type carrier arranged for reciprocatory movement, a type removably mounted thereon and situated normally in a position inaccessible to the operator, a manually operable latch for holding said type in operative position, and manipulative means for arresting said carrier, during a machine operation, at a position where the type is accessible to the operator, so that said latch may be readily disengaged from said type.

5 4. In a machine of the class described, operating mechanism, a plurality of type carriers, a type removably mounted on one of said carriers and situated normally in a position inaccessible to the operator, means whereby the said one carrier may be moved alone, and means for arresting movement of the carrier, during a machine operation, at a position where the type is accessible to the operator, to facilitate a change of the type.

10 5. In a machine of the class described, a movable type carrier, means to normally impart a complete cycle of movement to the type carrier during each machine operation, and optionally operable means for stopping the type carrier in an intermediate position, and for holding it in this position after the machine completes its cycle.

15 6. In a machine of the class described, operating mechanism, a keyboard, a movable type carrier, means to normally impart a complete cycle of movement to the type carrier during each machine operation, and a means controlled from the keyboard for preventing the type carrier from returning to its original position during the machine operation.

20 7. In a machine of the class described, a type carrier, means for moving said carrier through a normal operation including advancing and retracting movements, a type removably mounted on said carrier, and means for interrupting the normal operation of said carrier at a point where said type may be readily changed.

25 8. In a machine of the class described, a type

carrier, means for moving said carrier through a normal operation including advancing and retracting movements, a type removably mounted on said carrier, means for interrupting the normal operation of said carrier and latching it at a point where said type may be readily changed, and a manipulative means for releasing the latching means to enable the carrier to complete its operation.

30 9. In a machine of the class described, operating mechanism, a type carrier adapted to be advanced and retracted during the cycling thereof, means for normally latching the carrier against movement, a key, means controlled by the key for releasing the latching means to enable the carrier to rise, and additional means controlled by the key for altering the normal operation of the machine to arrest the carrier in its raised position.

35 10. In a machine of the class described, operating mechanism, a movable type carrier, a type removably mounted therein and normally situated in a position inaccessible to the operator, means normally latching the carrier in such position, a manipulative means, means controlled by the manipulative means for disengaging said latching means, and additional means controlled by the manipulative means for arresting the operating mechanism and the carrier when the type has been moved to a position accessible to the operator.

40 11. In a machine of the class described, a reciprocable type carrier, means for moving said carrier through its advancing and retracting movements, a type removably mounted on said carrier, key controlled latch means for normally restraining said carrier from advance movement, a second key controlled means for interrupting the normal operation of said carrier at a predetermined point, and means coupled with the second key controlled means for withdrawing the first key controlled latch means to enable the carrier to advance to such point.

WALTER A. ANDERSON.
